US00D875780S

(12) **United States Design Patent** (10) **Patent No.:** **US D875,780 S**
(45) **Date of Patent:** **** Feb. 18, 2020**

(54) **DISPLAY SCREEN OR PORTION THEREOF
WITH GRAPHICAL USER INTERFACE**

D341,848 S 11/1993 Bigelow et al.
5,465,401 A 11/1995 Thompson
D387,045 S 12/1997 Yamamoto et al.

(Continued)

(71) Applicant: **Apple Inc.**, Cupertino, CA (US)

(72) Inventors: **Patrick Lee Coffman**, San Francisco, CA (US); **Maxwell O. Drukman**, San Francisco, CA (US); **Chun Kin Minor Wong**, Cupertino, CA (US)

(73) Assignee: **Apple Inc.**, Cupertino, CA (US)

(**) Term: **15 Years**

(21) Appl. No.: **29/697,370**

(22) Filed: **Jul. 8, 2019**

Related U.S. Application Data

(63) Continuation of application No. 29/677,320, filed on Jan. 18, 2019, now Pat. No. Des. 853,432, which is a continuation of application No. 29/642,747, filed on Apr. 2, 2018, now Pat. No. Des. 838,739, which is a continuation of application No. 29/593,830, filed on Feb. 13, 2017, now Pat. No. Des. 814,509, which is a continuation of application No. 29/551,030, filed on Jan. 8, 2016, now Pat. No. Des. 778,941.

(57) **CLAIM**

The ornamental design for a display screen or portion thereof with graphical user interface, as shown and described.

DESCRIPTION

The FIGURE is a front view of a display screen or portion thereof with graphical user interface showing the claimed design.

The outermost broken lines in the FIGURE show a display screen or portion thereof, and form no part of the claimed design. The other broken lines in the FIGURE show portions of the graphical user interface that form no part of the claimed design.

1 Claim, 1 Drawing Sheet
